MYRINGOTOMY TUBE INSERTER

James L. Geraci, Cincinnati, Ohio, assignor to
Xomox Corporation, Cincinnati, Ohio

Filed Nov. 2, 1971, Ser. No. 195,065

Term of patent 14 years

Int. Cl. D24—02

U.S. Cl. D83—12

FIG. 1 is a perspective view of a myringotomy tube inserter embodying my new design.

FIG. 2 is an elevational view of the right end of FIG. 1.

FIG. 3 is an end elevational view of the left end of FIG. 1.

FIG. 4 is a top plan view thereof.

FIG. 5 is a side elevational view of FIG. 4.

FIG. 6 is a bottom elevational view of FIG. 4.

FIG. 7 is a perspective view of a modification of the myringotomy tube inserter illustrated in FIG. 1.

FIG. 8 is an elevational view of the right end of FIG. 7.

FIG. 9 is a side elevational view of the device of FIG. 7.

I claim:

The ornamental design for a myringotomy tube inserter, as shown and described.
